ENVELOPE FOR ARTICLE DISPLAY

Carlton L. Whiteford, Woodway Ridge Lane,
New Canaan, Conn.

Filed May 12, 1960, Ser. No. 60,549

Term of patent 14 years

(Cl. D58—2)

FIG. 1

The side and end view not shown are the same as the respective side and end shown.

The dominant features of my design reside in the portion shown in full lines.

I claim:

The ornamental design for an envelope for article display, as shown and described.
